DRAFTING IMPLEMENT

Julius C. Hochman, New York, N. Y., assignor to
Eagle Pencil Company, a corporation of Delaware.

Application February 15, 1933, Serial No. 656,776

11 Claims. (Cl. 33—151)

My invention is concerned with drafting compasses of the particular type disclosed in the prior patent to George Oberbeck, 730,388, of June 9, 1903, a construction, of which many thousands 5 have been made and marketed in the United States during the past thirty years.

Among the particular objects of the present invention, are to reduce the cost of manufacture by making the device of a reduced number of 10 stampings and facilitating the assembly thereof, yet affording a construction of enhanced ruggedness less likely to get out of order with superior friction clutching action for each setting of the legs and of improved appearance.

15 Other objects will be in part obvious and in part pointed out hereinafter.

In the accompanying drawing in which are shown one or more of the various possible embodiments of the several features of the invention,

20 Fig. 1 is a side view on an enlarged scale of a preferred embodiment of the compass;

Fig. 2 is a transverse view on the line 2—2 of Fig. 1;

25 Fig. 3 is a view similar to Fig. 2 prior to application of the rivet;

Fig. 4 is a transverse sectional view on the line 4—4 of Fig. 1;

30 Figs. 5, 6, 7, and 8 are transverse sectional views respectively along the lines 5—5, 6—6, 7—7, and 8—8 of Fig. 1; and

Fig. 9 is a perspective view of the handle web unit.

Referring now to the drawing, the compasses 35 comprise a pair of legs 10 and 11 of sheet metal, preferably sheet steel. These legs in the preferred embodiment are of widened area at their upper or pivot ends and each has an outwardly extending flat embossed area 12 affording a narrow rim 13. The handle member 14 on the compass has unitary therewith a web piece 15 interposed between the widened areas of the respective legs and preferably completely covered by said widened areas. To retain the three elements, 40 namely, the two legs 10 and 11 and the interposed web 15 of the handle member in assembled relation, a rivet 16 is preferably employed, the heads of which rest in corresponding countersinks 17 and 18 in the respective widened embossments of the legs, said rivet, when tightened, 45 as shown in Fig. 2, drawing the countersunk portion as originally spaced from the web, as at 19, into friction clutch relation with but slight clearance from the opposite faces of web 15 as at 20 50 in Fig. 2. Thus while the embossments serve to

stiffen the legs, as desired, the widened area about the rivet serves the additional function of a resilient friction washer and an improved friction clutch action is thus provided, without resort to washers, springs or other auxiliary pieces 5 for that purpose.

Preferably, the web stamping has integral therewith a cylindrical collar mount 22 which is formed by bending about a mandrel (not shown) a rectangular extension unitary with the web. Over the said cylindrical mount there is frictionally telescoped an ornamental handle cap member 14 which may be of drawn metal and may exert a clamping fit to partly close up the gap 23 in the split cylinder 22 and afford a particularly effective friction mount.

Centering means is provided to retain the handle mount at all times in symmetrical position with respect to the compass legs regardless of the radius for which the latter are set. For this purpose the legs are associated with respect to web 15, by coacting track and runner elements generically of the type of the Oberbeck patent, but of improved character.

In a preferred embodiment the web 15 is provided with a pair of arcuate slot segments 26 and 27 symmetrical with respect to the axis of the web and eccentric with respect to the rivet 16. Each compass leg has a runner stud 28 unitary therewith, said studs protruding into the respective slot segments 26 and 27. While the stud pieces may be separate elements screwed or forced into corresponding apertures in the legs, it is preferred to form said studs integrally with the respective legs, by a simple swaging operation, best suggested in Fig. 4. A punch (not shown) of diameter larger than said stud effects a depression 30 in the metal of the leg and thus forces outwardly from the opposite face of the leg the protruding stud 28 integral therewith. As best shown in Fig. 1 the stud for each leg is located at the rim thereof, which rim is locally widened as at 31 and the embossed area 12 correspondingly narrowed or notched to accommodate such stud. The studs extending from the two legs into the respective segment slots of the web plate are symmetrical with respect to each other, so that the handle knob 14 necessarily remains in symmetrical position with respect to the legs regardless for what radius the latter are set.

By the arrangement set forth, the segment plate and its slots are completely concealed by the widened areas of the respective legs at their 55

respective pivot ends so that these parts are not readily tampered with.

Slot segments 26 and 27 being eccentric with respect to the rivet 16, the aperture for the rivet 16 through the web plate 15 is elongated as at 44 to permit the web with the handle 14 to ride upward or downward as the arms are adjusted in position.

One of the legs 11 is preferably provided with 10 an integrally extending unitary arc piece 35 concentric with the pivot, in the plane of the rim of said arm and bearing scale markings 36 for radius setting. The other leg 10 is provided with a scale reading or gauging tongue 37 integral 15 therewith bent downward through the thickness of the web plate 15, and for frictional engagement with the scale 35. By this relation the effectiveness of the pivot clutch is aided in maintaining the compass in said position.

20 The centering point of the compass may be a stylus 38 frictionally retained in a split sleeve 39 formed at the end of the corresponding arm 10. The pencil 40 may be retained in a split sleeve 41 unitary with the other arm 11 and may be clamped in position by a clutch which by itself is not my invention but included in the subject-matter of the copending application of Benjamin W. Hanle, Serial No. 636,508, filed October 6, 1932 now Patent No. 2,045,298, issued June 23, 1936. The clutch accordingly need not be described at length. It may be briefly noted that the clutch wedging member comprises a yoke piece 42 with inturned ears 43 fitting into apertures 44 of converging ears 45 unitary with the sleeve 41.

As shown in Fig. 1, the handle knob 14 may be of a polygonal cross section harmonizing with the generally angular modernistic effect of the entity.

While the invention has been shown applied 40 to a pair of compasses, it could, of course, be applied with equal effectiveness in a divider embodiment.

It will thus be seen that there is herein described apparatus in which the several features 45 of this invention are embodied, and which apparatus in its action attains the various objects of the invention and is well suited to meet the requirements of practical use.

As many changes could be made in the above 50 construction, and many apparently widely different embodiments of this invention could be made without departing from the scope thereof, it is intended that all matter contained in the above description or shown in the accompanying drawing shall be interpreted as illustrative and not 55 in a limiting sense.

Having thus described my invention, what I claim as new and desire to secure by Letters Patent is—

1. A pair of compasses comprising leg members each comprising a unitary blank widened at its pivoting end, a handle member having an integral web interposed between said widened leg members, a rivet retaining said members in assembled relation, and symmetrically arranged track and runner stud means serving to center the web with respect to the legs, said track means being elongated, curved and eccentric with respect to said pivot, both the track and the free end of the coacting runner stud members being 65 completely covered by the widened portions of the compass legs.

2. A pair of compasses comprising stamped metal leg members widened at their pivoting ends, a handle member having a web unitary therewith and interposed between said widened

leg members, a rivet retaining said members in assembled relation, and symmetrically arranged track and runner stud means serving to center the web with respect to the legs, said track means being elongated, curved and eccentric with respect to said pivot, said track means being disposed within the thickness of said web and the runner studs protruding inward toward the web from portions of the legs which are imperforate. 5

3. A pair of compasses including three stamped 10 elements including two legs and a handle having a web unitary therewith and interposed between said legs, a rivet retaining said members in assembled relation and affording a pivot for said legs, symmetrical elongated arcuate track segments extending into the metal of said web, and runner studs protruding from the respective legs into the respective track segments, said legs being imperforate at the region of said runner studs. 15

4. A pair of compasses comprising three stampings, including a pair of legs and an intervening web having a handle member unitary therewith and protruding above said legs, said legs widened to completely cover said web, a rivet through said legs and said web, elongated arcuate track slots 25 through said web symmetrically arranged and eccentric with respect to said rivet, and runner studs integral with the respective legs and swaged inward therefrom to protrude into the respective track segments. 30

5. A pair of compasses including a pair of leg stampings widened at their handle ends having the main area thereof embossed outward to afford a relative wide raised area near the handle ends, a web interposed between said legs and 35 having a handle knob unitary therewith and a rivet through said widened embossments forcing the areas thereof inward for friction clutch action.

6. A pair of compasses including a pair of leg 40 stampings widened at their handle ends, having the main areas thereof embossed outward to afford a relatively wide raised area near the handle ends, a web interposed between said legs and having a handle knob unitary therewith and a 45 rivet through said widened embossments forcing the areas thereof inward for frictional engagement, runner studs protruding toward the web from beyond the embossed areas of the respective legs and track segments in said web symmetrically arranged and accommodating the respective 50 runner studs.

7. A pair of compasses including sheet metal leg members widened near the handle, said leg members having the main central areas thereof 55 embossed outward to afford a flat surface raised with respect to the rims of said legs and of substantial width near the handle end, said rims locally widened and said embossed areas correspondingly narrowed, runner studs swaged inward from the widened rim regions, said web portion having track segments symmetrically arranged and accommodating the respective studs, and a rivet through the embossed widened areas of the respective legs and the interposed web 65 drawing said embossed areas toward said web for friction clutch action.

8. A pair of compasses including sheet metal legs, an interposed web having a handle knob unitary therewith, and a rivet connecting said 70 elements together, each of said legs having a stiffening web embossed therein and a plane rim, an arcuate scale concentric with said rivet, integral with one of said legs and substantially in the plane of said rim, the companion leg having 75

a gauging tongue protruding therefrom and bent through substantially the thickness of said web for snug engagement with the arcuate scale.

9. As an article of manufacture, a compass leg including a sheet metal stamping of widened area at its pivot end, having a flat outward embossment affording a narrow peripheral rim, said rim locally widened and said embossment correspondingly reduced at said area, and a stud swaged inward from said widened region of the rim.

10. A pair of compasses of the type including pivoted legs and an operating handle, said handle comprising a stamping including a web interposed between said legs, and a split tube portion unitary with said web and a handle cap frictionally telescoped over said tube portion.

11. A pair of compasses including sheet metal legs, an interposed web having a handle knob unitary therewith, centering means between the web and the respective legs to maintain the handle knob symmetrical with respect to said legs 5 in all positions of adjustment of said compass, a rivet connecting said legs and web together and exerting friction clutch action, an arcuate scale concentric with said rivet and integral with one of said legs and a tongue integral with the other 10 of said legs and bent out of the plane of said legs through substantially the thickness of said leg to contact and exert a friction clutching action against said arcuate scale.
